UNITED STATES PATENT OFFICE.

WILLIAM W. OWEN, OF ELGIN, AND CHARLES M. CANDY, OF CHICAGO, ILLINOIS,
ASSIGNORS TO AUTOMATIC ELECTRIC COMPANY, OF CHICAGO, ILLINOIS, A COR-
PORATION OF ILLINOIS.

AUTOMATIC TELEPHONE SYSTEM.

Application filed July 25, 1918. Serial No. 246,643.

To all whom it may concern:

Be it known that we, WILLIAM W. OWEN and CHARLES M. CANDY, citizens of Elgin, Kane County, Illinois, and Chicago, Cook County, Illinois, respectively, have invented certain new and useful Improvements in Automatic Telephone Systems, of which the following is a specification.

Our invention relates in general to improved mechanism and circuits for use in an automatic telephone system and more specifically to an improved method of signalling a called subscriber in such a system.

In the past it has been the custom when calling party lines to provide a plurality of groups of connector switches having access to each group of party lines, each group of connectors ringing with a different frequency, so that in order to call a subscriber on such party line, the calling man must pick out the group of connectors which has the proper frequency and use a connector in such group to call the line. It will be seen that each line must be multiplied into four groups of connectors, in a four party line system, and no matter how few party lines there are there must always be as many groups of connectors as there are parties on a line. It has been the common practice in later systems to use the so called jack per station scheme in connection with such a system so that when a subscriber moves from one part of town to another his phone may still be given the same call number, although he may use a different line switch to call. Such a scheme is well known to the art and it is thought a detailed description will be unnecessary. This jack per station scheme is the simple method of connecting the subscribers' lines and the contacts of the connector banks to idle strips of contacts on a so called intermediate distributing frame so that jumpers may be connected from the line terminal strips to those of the connector bank contacts. Thus if a line is moved to a line switch in a different section, the jumper from this new line switch terminal block will be connected to the terminal strip of the same contacts in the connector over which the line was previously called, thus retaining the same called or directory number.

One objection to such a scheme has been encountered; namely, when a subscriber on

a four party line is moved to another part 55 of the exchange, he must, it will be seen, be put on to another four party line in his new section which has an idle place for a station of his particular frequency, that is, there must be no subscriber on the new line 60 having the same frequency bell, as the old call number which he desires to retain will always use the same frequency, coming as it does from a particular group of connectors. 65

The main object of our invention therefore is to provide improved circuits so that the character of the signalling current applied by a connector when calling a certain called number may be varied at will, so 70 that when moving a subscriber, he may be added to any line regardless of the character of the stations already there and may be called by the same number, but in calling this number any desired frequency may 75 be applied to the line and if there is already a station on the line to which he has moved which has the same frequency as he formerly had then the circuits are adjusted to apply the frequency corresponding to the 80 vacant space on that line.

In order to accomplish this and other results we have made the ringing relays of the lines individual to the sets of contacts in the connector banks, and each is so arranged as to apply any one of a plurality of frequencies to the line which may be connected thereto by jumpers, thus making it possible to call party lines through the medium of only one group of connectors. 90

Referring to the accompanying drawings, Fig. 1 shows a connector switch H and a called line A accessible thereto, also showing the multiple contacts of said line in the same connector for calling any one of the 95 parties on said line.

Fig. 2 is a schematic representation of the intermediate distributing frame showing the arrangement of the jack per station scheme as applied in accordance with the 100 principles of our invention.

Fig. 3 is an alternative method of applying our invention and shows a connector H' and a called line A' with its multiples.

Referring first to Fig. 1 we will explain 105 the operation of the apparatus in detail when the connector H is seized by a calling subscriber and operated to connect with and

signal a subscriber on the line of substation A.

When the connector H is seized by a selector or line switch, depending upon the size 5 of the system, a circuit is closed in the usual manner for line relay 2 which closes a circuit for slow relay 3. Relay 3 prepares a circuit for slow series relay 4 and vertical magnet 5 and opens a point in the 10 circuit of release magnet 6. As soon as relay 2 is operated by the impulses of a digit of a called number, it falls back a number of times to operate magnet 5 a predetermined number of times and to energize relay 4. Magnet 5 operates to step the wipers 7 to 10 inclusive to some level of the connector bank in which the desired line is located. Relay 4 upon falling back after 15 this series of impulses prepares a circuit for the rotary magnet 11 and relay 12 in multiple through springs 13 which were closed on the initial movement of the switch. As soon therefore as relay 2 operates in 20 response to the next digit the circuit of magnet 11 is closed a number of times to step the wipers 7 to 10 inclusive to the desired contacts of the bank and slow relay 12 is energized and maintained energized 25 for a second after the impulses cease.

30 Should the called line be busy a ground will be present on the private contact thereof and will flow over wiper 9, through springs 14 and 15, and relay 16 to battery. Relay 16, upon energizing, connects 35 the busy circuit from the device M to the calling line circuit to indicate the busy condition of the called line, opens the circuit of the magnet 11 and relay 12, and locks itself to ground through springs 17, 18 and 40 19. Whereupon the calling subscriber may release and call again. Assuming the called line to be idle, then relay 16 will not be energized and as soon as relay 12 falls back a circuit will be closed for the upper winding 45 of relay 20 extending from ground through springs 19, springs 18, upper winding of said relay, springs 21 and 14, wiper 9, and through bridge cut off relay 22 and magnet 23 to battery. Relays 20 and 22 50 only, energize at this time due to their comparatively high resistance. Relay 20 opens the circuit of magnet 11, closes springs 24 and 25, connects ground through spring 26 and its front contact direct to wiper 9, and 55 also to hold itself energized through its lower winding. The direct ground on wiper 9 maintains the called line busy to further calls at its multiples, and holds relay 22 energized. A further result of the 60 energization of relay 20 is the closure of springs 27 with the following result. Ground is connected through springs 28 of the ring cut off relay 29, through springs 27, through a special wiper 10 and a contact 65 30 through the relay 34 of a board of

ringing relays which may be located preferably on or near the intermediate distributing frame. This particular relay 34 is one of four relays allotted to this four party line, each relay being individual to one of 70 four sets of multiplied contacts associated with this line. It will be understood that these four multiplied sets of bank contacts may be arranged in a row either vertically or horizontally without changing the operation. For instance, the numbers allotted 75 to this particular party line when first installed may be 1111, 1112, 1113 and 1114 and the contacts will therefore be the first, second, third, and fourth sets of contacts 80 in the first level of this connector bank. It is understood that there will in practice be more than one connector having access to this party line and therefore each set of contacts may be multiplied into as many 85 connectors as traffic conditions demand. It will be assumed that the subscriber A is allotted the number 1114 and the connector is operated to the fourth set of contacts 90 in the first level. Then as soon as the switch cuts through as described and relay 34 is energized, it will apply generator from the 16 cycle generator by way of springs 36 and 37 of interrupter relay 35, jumper 38, springs 39 of relay 34, contact 40, jumper 41, to and through the ringers of the various stations of the called line, back through jumper 42, wiper 7, springs 24, springs 43 and 44, and upper winding of 95 relay 29 to battery. As the bell of substation A is of the 16 cycle character this bell only will operate and as soon as the receiver at said substation is removed, a direct current circuit will be closed for relay 29 which 100 relay immediately energizes and locks itself to ground through springs 19. Relay 29 also opens the circuit of relay 34 at springs 28 and said relay falls back to disconnect the generator current, relay 29 also closes springs 45 and 43 and springs 46 to 105 cut the connection through to the called subscriber in the usual manner.

Now if the number 1113 had been called then the contacts 47 to 50 inclusive, would have been connected with and relay 33 115 would in this case be operated to connect 50 cycle generator to the called line to signal some other station thereon. Relays 31 and 32 are of similar nature and would be operated when the numbers 1112 and 1111 120 are called.

Referring now to Figure 2 we will explain how the cross connection is made and the operations necessary should a line be moved from one section to another.

In this Fig. 2, 51 represents a subscriber's line cable from the main distributing frame which is fanned out on the I. D. F. or intermediate distributing frame to vertical rows of terminals. The terminals 52, 130

53 and 54 represent the terminals to which the four party line of substation A (Fig. 1) is connected, the two line conductors thereof leading to terminals 53 and 54 and 5 the terminal 52 representing the private normal of the line switch allotted to this line. The cable 55 leads from the vertical terminals to a line switch board represented at E which line switches have access 10 through selectors at F to connectors at G. The various sets of contacts from the connector banks are carried through a cable 56 and fanned out on a row of horizontal terminal sets at the right of the figure, thus 15 the first set of line and private contacts in the lower bank leads to contacts marked 1111. In a single station line such as represented at contacts 57, 58 and 59 a jumper 60 is simply connected to the called number 20 contacts of that line such as 1118. In this case when 1118 is called the relay 1118 will pull up and apply ringing current of any desired frequency to that line depending upon which generator the front contact 25 of relay 1118 is connected to by its jumper. In the case of a four party line however, the terminals 52, 53 and 54 are multiplied to a set of four so-called idler block terminal sets, as shown. Then if the first party 30 is #1111 then the jumper from contacts 1111 is connected thereto and relay 31 is used to signal that party. We have shown the numbers 1111, 1112, 1113, and 1114 as allotted to this line as explained in connection with Figure 1. Let us assume that 35 the subscriber A whose number is 1114 and who is now signalled by 16 cycle current from relay 34, desires to move to some other part of town and his telephone line 40 comes in on some other line switch. Of course he will still desire to be on a four party line and retain the same call number. In this case suppose that the section into which he is moved has only one vacant 45 space which is on another party line already having three stations thereon, one having a 16 cycle ringer, one a 50 cycle and another a 66 cycle. Now this other line will have a similar set of idler block 50 terminals multiplied thereto and the jumper 61 from contacts #1114 will be removed from the contacts 62, 63 and 64 and connected to the idle block of the new party line. Now as there is already a 16 cycle 55 station on this party line then the ringer of substation A must be changed to 33 cycle and the front contact of relay 34 must be jumpered to one of the terminals such as 65 leading to the 33 cycle generator. 60 Now when 1114 is called the connector operates in the usual manner to pick out contacts 1114 and energize relay 34 which relay now applies 33 cycle generator to the line of substation A to signal the subscriber thereto. It will thus be seen that the 65

subscribers may be changed from single to party lines or vice versa or from one party line to another regardless of the character of the stations already there and that the connectors or the call numbers 70 need never be changed. Also it will be seen that each call number or set of contacts in the connector has a ringing relay individual thereto which may apply any frequency of current to the line. 75

In Figure 3 we have shown a modification of the scheme shown in Figures 1 and 2. In this case we have adapted our invention to a connector switch having only three wipers. The relays 131 to 134 inclusive, instead of being in circuit with a fourth wiper of the connector are in series with the regular private wiper. These relays 134, etc., are of such a character that they will energize only when the special battery X is included in circuit therewith. We will explain only the operation of these relays, it being understood that the majority of the relays and parts shown are exactly similar to those shown in Fig. 1. 80 85

This connector H' operates as the connector H (Fig. 1) to connect with any of four multiples of the line of substation A', and after the connection is established therewith and the line is found idle, relay 120 pulls up in the usual manner and closes the springs 127, which connects the battery X through wiper 109 and in series with special relay 134, assuming that 1114 is called. Relay 134 connects generator to the line in the same manner as did relay 34 Fig. 1. As soon as the called subscriber answers, relay 129 energizes to cut off battery X at springs 128 and cuts the connection through in the usual manner. It 90 95 100

will be seen that each relay is energized only when connection is extended to its particular multiple in spite of the fact that all the privates are multiplied together as each relay is connected in the branch of the multiples extending to its particular set of contacts. In all other respects Fig. 3 is similar to Fig. 1 and might easily be laid out in the same manner as shown in Fig. 2. It will therefore be seen that we have provided a 105 110 115

novel and very useful method of signalling called subscribers in a jack per station system which enables a party to be moved without regard to frequency or other details to any part of the system and on any line therein by a simple method of cross connection. 120

Having fully described and ascertained the features and objects of our invention, what we consider to be new and desire to have protected by Letters Patent will be pointed out in the appended claims. 125

What we claim as our invention is:

1. In a telephone system, an automatic switch, a plurality of lines accessible to said

switch, means for operating said switch to extend a talking circuit to one of said lines, a relay individual to each line, and means for operating one of said relays over a circuit independent of the talking circuit to signal the associated line when connection is extended thereto.

2. In a telephone system, a party line, an automatic switch for extending a talking circuit to said line, a plurality of substations on said line, a ringer for each station, a plurality of relays individual to said line, one for each station, and means for operating any of said relays over a circuit independent of said talking circuit to signal its station.

3. In a telephone system, a line, a plurality of stations on said line, a plurality of branches for said line, an automatic switch having means for extending a talking circuit to any of said branches, and means individual to each branch operated over a circuit separate from said talking circuit when connection is extended thereto for signalling a certain one of said stations.

4. In a telephone system, a line, a plurality of stations on said line, an automatic switch having access thereto, means for operating said switch by only the last two digits of the call number of said line to extend a talking circuit to said line, and means controlled over a circuit separate from the talking circuit for signalling any of the stations on said line automatically controlled by the operation of the switch when connection is extended to the line.

5. In a telephone system, an automatic switch, a plurality of lines, a plurality of sets of contacts associated with said switch and accessible thereto, means for connecting any one of said lines to a pair of contacts of any set of contacts, a relay individual to each set of contacts and connected to another contact of said set separate from the line contacts, a plurality of sources of signalling current, means for associating said relay with any of said sources of current, and means controlled by the connection of said switch with a set of contacts, for operating the relay associated therewith to apply the associated source of current to the line associated with the set of contacts.

6. In a telephone system, subscribers' lines, a plurality of stations for each line, signalling devices for each line, a ringing relay for each station on each line, means for extending a talking circuit to said line and for operating one of said relays over a circuit separate from the talking circuit to operate the signal of one of said stations, and means for causing said relay to apply any frequency of current to said line without changing the call number thereof.

7. In a telephone system, subscribers' lines, a plurality of stations on each line, signal-

ling devices for each line, a ringing relay for each station on each line, automatic switching means for extending a talking circuit to said line and for operating one of said relays over a circuit separate from the talking circuit to operate the signal of one of said stations, and means for causing said relay to apply any frequency of current to said line without changing the call number thereof.

8. In a telephone system, a subscriber's line, a plurality of stations on said line, a plurality of sources of signalling current, means for extending a talking circuit to said line, a plurality of relays individual to said line, one for each station, and means for energizing any of said relays over a circuit separate from the talking circuit to apply one of said sources of current to the line to signal the station associated with said relay.

9. In a telephone system, an automatic progressively movable switch having a plurality of sets of bank terminals individual thereto, a plurality of telephone lines, and means for connecting any terminal to any line, a relay individual to each set of terminals, one of said relays always energized when connection is made by said switch to the terminal individual to said relay to signal a station on the line to which it is connected, and means for causing said relay to apply any one of a plurality of sources of current to its connected line.

10. In an automatic telephone system, a party telephone line, a calling branch for said line terminating in an automatic switch, a plurality of called branches for said line, a ringing relay individual to each called branch, sources of ringing current of different character, a distributing frame on which said line and said called branches are connected by jumpers, a second distributing frame on which each relay is connected to a different one of said sources, automatic switches for completing connections to said line by way of the called branches, and means in each switch for operating the relay associated with any branch in use to selectively signal the desired station.

11. In an automatic telephone system, a party telephone line, a calling branch for said line terminating in an automatic switch, a plurality of called branches for said line, a ringing relay individual to each called branch, sources of ringing current of different character, a permanent connection between said line and calling branch and between each called branch and its associated relay, a distributing frame on which said line and called branches are temporarily connected by jumpers, a second distributing frame on which said relays are temporarily connected each to a different one of said sources, automatic switches for completing connections to said line by way of the called

branches, and means in each switch for operating the relay associated with any called branch in use to selectively signal the desired station.

- 5 12. In an automatic telephone system, a party telephone line, a calling branch terminating in an automatic switch for use in extending out going calls from said line, a plurality of called line branches, connector switches having access to said called line branches for completing incoming calls to said line, a ringing relay individual to each of said branches, different sources of ringing current associated with said relays, a permanent connection between said line and calling branch, a distributing frame on which said line and the said called branches are temporarily connected by means of jumpers, a second distributing frame on which each of said relays is temporarily connected to one of said current sources, and means in each connector effective when the same is used to complete an incoming call for operating the relay associated with 25 the called branch in use to selectively signal the desired station on said line.

13. In an automatic party line telephone system, a plurality of party lines, a plurality of connector switches, called branches for said lines, each branch being assigned a separate telephone number and being terminated in the banks of a number of said connectors, means whereby any party line may be readily connected to any desired plurality of said branches at will and whereby any connected branch may be easily shifted to any other party line, a plurality of different sources of ringing current, and means whereby any one of said sources may be readily associated with any desired branch and whereby any branch in use may be changed at will with respect to the ringing current source with which it is associated, whereby a telephone station may retain its number when connected to a new party line regardless of whether or not such new party line has a vacancy which corresponds to the ringing current source which was associated with said station on the old party line.

14. In an automatic party line telephone system, party lines, connector switches, means for connecting any party line with any desired sets of contacts in the banks of said connectors and for changing any contact set to a different party line at will,

sources of ringing current of different character, and means for associating any source with any set of bank contacts and for readily changing any set of bank contacts with respect to the ringing current source with which it is associated, whereby a given set of bank contacts may be assigned to any party line and to any station on such party line regardless of the ringing current source to which such station is adapted to respond.

15. In a telephone system, a party line, a station on said line responsive to a particular kind of ringing current, automatic switching mechanism at the exchange for connecting with the line of said station when the number of the station is called and for transmitting the correct ringing current to signal said station, another party line having a vacancy which corresponds to a different kind of ringing current, means whereby the said station may be called by means of the same switching mechanism and the same number after it is connected to the said second line, the ringer at said station having been changed to adapt the station to respond to the ringing current corresponding to the said vacancy, and means co-operating with said switching mechanism for transmitting the correct ringing current to signal said station when the station is called on the new line.

16. In a selective ringing telephone system, a party line, a station on said line having signalling arrangements different from the signalling arrangements at any other station on said line, automatic switching mechanism at the exchange for connecting with the said party line when the number of the said station is called and for selectively signalling the said station, another party line having a vacancy which corresponds to a substation signalling arrangement differing from the signalling arrangement at said station, means whereby the said station may be called by means of the same switching mechanism and the same number after it is connected to the said second line, the signalling arrangements at said station having been changed to correspond to said vacancy, and means for causing said switching mechanism to selectively signal said station when the same is called on the new line.

Signed by us at Chicago, Cook County, Illinois, this 22nd day of July, 1918.

WILLIAM W. OWEN.
CHARLES M. CANDY.
